GASEOUS ELECTRIC DISCHARGE LAMP
DEVICE

Joseph Dellian, Berlin-Treptow, Germany, assignor to General Electric Company, a corporation of New York

Application November 27, 1933, Serial No. 700,007
In Germany December 7, 1932

4 Claims. (Cl. 176—1)

The present invention relates to gaseous electric discharge lamp devices generally and to circuits for such devices.

Gaseous electric discharge lamp devices are operated successfully in parallel by connecting them through series resistances. The object of the present invention is to improve the luminous efficiency of such circuits. Another object of the invention is to facilitate the starting of the gaseous electric discharge devices in such a circuit. Still further objects and advantages attaching to the device and to its use and operation will be apparent to those skilled in the art from the following particular description.

In accordance with these objects the invention comprises two or more gaseous electric discharge lamp devices connected in parallel through series resistances and the series connected resistance of each device is mounted in or on a device other than the device to which said resistance is connected in series in the circuit. An auxiliary discharge takes place between the series resistance and one of the electrodes of the device in or on which said resistance is mounted which discharge ionizes the gaseous filling to facilitate the starting of the main discharge in the device. The resistance also serves to heat the container, the gas filling, the vaporizable material and the electrodes of the device in or on which it is mounted quickly to their operating temperature which also facilitates the starting of such devices and increases the efficiency thereof. While the series resistance can be in many forms, discussed later herein, I prefer a filament adapted to be heated to incandescence mounted in the container of the device. The filament emits light to increase the intensity and to supplement the color of the light emitted by the gaseous electric discharge in the device and thus increases the luminous efficiency of the circuit. When a gaseous electric discharge device is connected across a line the series resistance in the form of a filament cannot be mounted in the container of the device to which it is electrically connected due to the great difference in potential between said filament and the electrodes which results in a discharge between these two elements of the device during the operation thereof which quickly destroys the filament. When two or more devices are connected in parallel in a circuit the arrangement of the incandescent filament in a container of a device other than the device to which the filament is connected in series, in accordance with the present invention, is possible and practicable since the filament voltage and the discharge voltage in the

last named device can be made approximately the same to avoid an electric discharge between the filament and the other elements of the device during the operation thereof.

In the drawing accompanying and forming part of this specification two embodiments of the invention are shown, in which

Fig. 1 is a schematic view of two gaseous electric discharge devices connected in accordance with the present invention, and

Fig. 2 is a similar view of a gaseous electric discharge device having two discharge paths connected in accordance with the present invention.

Like numbers denote like parts in both the figures.

Referring to Fig. 1 of the drawing the new and novel circuit comprises two gaseous electric discharge devices having similar structures. One of said devices comprises a container 1, electrodes 2 and 3 mounted on current supply leads 5 and 7 sealed into the container 1 and a filament 4 extending along and beyond the discharge path between said electrodes 2 and 3. The electrodes 2 and 3 are self-heating, thermionic electrodes of the sintered, mixed metal and oxide type known in the art as Pirani electrodes and the filament 4 is a tungsten filament. Said container 1 has a gaseous atmosphere therein comprising a rare gas, such as neon, a metal vapor, such as mercury vapor, or a mixture of rare gases, such as neon and argon, or a mixture of rare gas and metal vapor, such as a mixture of argon and mercury vapor, or neon and sodium vapor, or any of the starting gas-metal vapor mixtures known in the art. The respective similar parts of the other gaseous electric discharge device are denoted by the primes of the same numbers with the exception that the electrodes 2' and 3' are mounted on current leads 6 and 8 respectively sealed into said container 1'. Said filament 4 is connected to the current supply lead 5 of said electrode 2 and to the current supply lead 6 of the electrode 2'. The filament 4' is connected to the current supply lead 8 of the electrode 3' and to the current supply lead 7 of the electrode 3. Said current leads 5 and 8 are connected to the terminals of a 110 or 220 volt source of current (not shown for purposes of simplicity). The two gaseous electric discharge devices are thus connected in parallel and the filament 4 is a series resistance for the discharge path in the device having container 1 and the filament 4' is a series resistance for the discharge path in the device having the container 1'.

When potential is applied to the above de- 55

scribed circuit glow discharges are formed between the electrode 3 and the part of the filament adjacent thereto and between the electrode 2' and the part of filament 4' adjacent thereto. These glow discharges ionize the gas in the discharge path in the respective devices to facilitate the starting of the main gaseous electric discharge therein. When the main discharge has been started in the respective devices the filaments 4 and 4' are heated to incandescence by the discharge current and emit light to supplement the light emitted by the gaseous electric discharge in the devices. The heat from the incandescent filaments 4 and 4' maintains the containers 1 and 1', the gas filling, and the vaporizable material, if any, at an elevated temperature during the operation of the devices which is of particular importance when a difficultly vaporizable material, such as an alkali metal vapor, forms the gaseous atmosphere or is a component of the gaseous atmosphere in order to obtain an effective metal vapor pressure.

Another embodiment of the invention is illustrated in Fig. 2 of the drawing. In this embodiment two discharge paths are in parallel positions in a single container 9 and the electrodes 2 and 3, 2' and 3' and the filaments 4 and 4' are connected as described in conjunction with Fig. 1 and the gaseous atmosphere is similar to those described in conjunction with Fig. 1. The container 9 is provided with a conventional screw-base 10 having two contacts to which the current leads for the electrodes 2 and 3' are connected. The interior of said container 9 is divided by a partition 13 which separates the two discharge paths. When the gaseous atmosphere in the chambers 11 and 12 of the container 9 is of a different kind, or at different pressures the partition 10 is gas tight. When the pressure and the gas filling is the same in all parts of the container 9 the partition is made of metal gauze or net having a suitable potential applied thereto. The vaporizable material, such as mercury, sodium, cadmium or the like is indicated by pools 14 and 15. When three phase operation is desired three chambers similar to 11 and 12 are arranged symmetrically in a container, and the device is connected in such manner that on each phase of the 3 phase current the discharge path in one chamber and the series connected filament thereof mounted in an adjacent chamber gives light. A very steady light is thus made available for use in the arts generally.

While I have shown and described and have pointed out in the annexed claims certain novel features of the invention, it will be understood that various omissions, substitutions and changes in the forms and details of the device illustrated and in its use and operation may be made by those skilled in the art without departing from the broad spirit and scope of the invention, for example, the electrodes of the above described devices are cold, sheet-metal electrodes or thermionic, indirectly heated, oxide coated, metal shell electrodes known in the art as Hull cathodes, when desired; the end parts of the incandescent filament are

insulated from and pass through or surround the thermionic electrodes to indirectly heat said electrodes, when desired; the known gases, vapors, or gas mixtures, or gas-vapor mixtures which emit light similar to daylight is used in the devices, when desired; the container is made of light diffusing glass to blend the light emitted by the different light sources therein, when desired; the lamp devices are enclosed in transparent heat conservators, when desired, and the series resistance is of sufficient thickness so that it does not emit light during the operation of the device or is a strip of material mounted in the interior or on the exterior of the device, when desired.

What I claim as new and desire to secure by Letters Patent of the United States, is:—

1. An electrical circuit comprising in combination, a plurality of gaseous electric discharge devices connected in parallel to the terminals of a current source, a series resistance for each of said devices, said series resistance being mounted in a device other than that device to which said resistance is connected in series to facilitate the starting of the device in which said filament is mounted.

2. An electrical circuit comprising in combination, a plurality of gaseous electric discharge devices connected in parallel to the terminals of a source of current, a series resistance for each of said devices, said series resistance being an incandescent filament mounted in the container of a device other than that to which said filament is connected in series to facilitate the starting of the device in which said filament is mounted and to supplement the light emitted thereby.

3. An electric discharge device comprising a container, electrodes sealed therein, a gaseous atmosphere therein, a partition in said container dividing said container into chambers electrically insulated from each other, a pair of said electrodes in each of said chambers, the gaseous electric discharges in said device being connected in parallel, a series resistance for each of said discharges, said resistance being mounted in a chamber other than that containing the gaseous electric discharge to which said resistance is connected in series to facilitate the starting of the discharge in the chamber in which said resistance is mounted.

4. An electric discharge device comprising a container, electrodes sealed therein, a gaseous atmosphere therein, a partition in said container dividing said container into chambers electrically insulated from each other, a pair of said electrodes in each of said chambers, the gaseous electric discharges in said device being connected in parallel, a series resistance for each of said discharges, each of said resistances being an incandescent filament and being mounted in a chamber other than that containing the gaseous electric discharge to which said filament is connected in series to facilitate the starting of the discharge in the chamber in which said filament is mounted and to supplement the light emitted thereby.

JOSEPH DELLIAN.
